Primary Examiner — Cynthia M. Chin(74) *Attorney, Agent, or Firm* — ANDRUS
INTELLECTUAL PROPERTY LAW, LLP(57) **CLAIM**

The ornamental design for a railing for a marine vessel as shown and described.

DESCRIPTION

FIG. 1 is a front perspective view of a railing for a marine vessel according to our new and ornamental design;

FIG. 2 is an isolated front perspective view thereof;

FIG. 3 is a rear perspective view thereof;

FIG. 4 is a front elevation view thereof;

FIG. 5 is an enlarged partial view, taken from FIG. 3; and FIG. 6 is an enlarged sectional view taken in the direction line **6-6** in FIG. 4.

The dash-dot broken lines represent the bounds of the claim and all other broken lines represent portions of the railing for a marine vessel and marine vessel that form no part of the claimed design. None of the broken lines form a part of the claim.
